UNITED STATES PATENT OFFICE.

STANLEY CZAPEK, OF DETROIT, MICHIGAN, ASSIGNOR TO RADIANT SPECIALTY COMPANY, A CORPORATION OF MICHIGAN.

DESIGN FOR A LIGHTING FIXTURE.

Application filed March 12, 1925. Serial No. 12,700. Term of patent 3½ years.

To all whom it may concern:

Be it known that I, STANLEY CZAPEK, a citizen of the United States, residing at Detroit, in the county of Wayne and State of Michigan, have invented a new, original, and ornamental Design for a Lighting Fixture, of which the following is a specification, reference being had to the accompanying drawing, forming a part hereof, in which—

Fig. 1 is a plan view showing only a part bearing the ornamental features, the remaining portion being a repetition of the completed portions shown.

Fig. 2 is a side elevational view of the invention as shown in Fig. 1.

I claim:

The ornamental design for a lighting fixture as shown.

STANLEY CZAPEK.
